J. T. FAIRHURST.
FOLDING PARTITION.
APPLICATION FILED JAN. 27, 1916.

1,224,155.

Patented May 1, 1917.

FIG. 1.

FIG. 2

FIG. 3

John T. Fairhurst, Inventor
By his Attorney
Thompson & Felt.

UNITED STATES PATENT OFFICE.

JOHN T. FAIRHURST, OF BROOKLYN, NEW YORK, ASSIGNOR TO THE FOLDING PARTITION COMPANY, A CORPORATION OF NEW JERSEY.

FOLDING PARTITION.

1,224,155.

Specification of Letters Patent.

Patented May 1, 1917.

Original application filed July 10, 1915, Serial No. 39,061. Divided and this application filed January 27, 1916. Serial No. 74,558.

To all whom it may concern:

Be it known that I, JOHN T. FAIRHURST, a subject of the King of England, residing at the borough of Brooklyn, in the county 5 of Kings and State of New York, have invented certain new and useful Improvements in Folding Partitions, of which the following is a specification, reference being had therein to the accompanying drawing.

10 My invention relates to improvements in folding or collapsing partitions and more particularly has reference to and is especially adapted for use with partitions of the class described where used in buildings for 15 separating rooms or offices and is a division of my co-pending application Serial No. 39,061.

Referring to the accompanying drawings, Figure 1 illustrates in perspective view, 20 partly broken away, an application of my invention as applied to a folding partition such as may be used in dividing off the rooms of a school although of course it will be readily understood that the invention 25 may be applied to cabinets, receptacles or for other similar purposes. Fig. 2 is an enlarged detail, partly in cross section and partly broken away, illustrating a device 30 adapted for insuring the proper folding of the sections of the partition, and Fig. 3 is a view of the same at right angles to the view shown in Fig. 2.

4 is the frame of the partition, and 5—5' the lower and upper guides thereof, the 35 guide 5' being cut away as indicated at 6 to allow the panels or sections such as 7—7' to pass outwardly for folding. The panel 7' it will be observed is cut away as indicated 40 at 8 to allow clearance for the tongue 9 shown to better advantage in Fig. 2. This tongue it will be observed is adapted to project downwardly at the side of the partition facing the observer looking at Fig. 1 so that unless said tongue is in alinement with said 45 cut away portion such as 8, the partition cannot be folded outwardly as shown in Fig. 1 thus insuring the correct position of the sections before the same are folded and preventing the buckling or binding of the 50 same within the guides.

The tongue 9 it will be observed is provided with an elongated cut away portion such as 10 shown to better advantage in Fig. 2 and is provided with the shank 11 adapted

to pass upwardly into the recess 12 so that 55 said tongue is normally seated upon the pin 13 and is provided with two opposite tapered sides such as 14—14' and the tapered side at the back such as 15 from which it will be seen that the flat side 16 engages 60 the top edge or face of the sections facing the observer looking at Fig. 1; thus making it impossible to fold the sections until the cut 8 is brought into alinement with the tongue 9, otherwise the guide such as 6 65 might become loose by the section such as 7 in an effort to fold the partition or section before the sections have moved sufficiently to the right looking at Fig. 1.

In other words, the flat side 16 of the 70 tongue 9, which faces the observer looking at Fig. 1 would strike against the inside top edge of the doors or sections 7—7' when opening the same out, unless the V cut 8 is brought in alinement therewith. This insures the opening of the sections or doors in proper position so as not to jam or break away the guide 6. Of course when sliding the doors the beveled sides 14—14'—15 allow the top of the doors or sections to push the 80 tongue 9 clear, thus causing no destruction when folding the doors, although insuring proper position of the doors or sections when being opened as aforesaid.

Of course it will be understood that various modifications may be made without departing from the spirit of the invention as claimed.

I claim:

1. In combination with a folding partition, a movable member adjacent the top guide thereof, and a cut away portion in one of the sections of said partition adapted to clear said member whereby said sections may be folded only when said member and said cut away portion are in alinement, said member having oppositely tapered surfaces at two sides and a substantially straight and a tapered surface respectively at the other two opposite sides. 10

2. The combination with a folding partition comprising sections hinged together in separate pairs, of means for guiding the free ends of said sections along the line into which the partition is designed to be extended, said guiding means including moldings arranged at either side of the line of extension, one of said moldings terminating

at a distance from the jamb sufficient to permit the pairs of sections to be folded when moved as near as possible to the jamb, and a depending movable latch arranged in line with the shorter molding and having an abrupt face presented to the longer molding for preventing the folding of the pairs of sections when moved beyond said shorter molding until after the sections nearer the jamb have been completely folded, one section of each pair having a notch adapted to register with said latch when said pair

being the next to be folded is advanced into close proximity to the folded sections, the edges of said latch being inclined to permit 15 the other section of each pair to ride over the same in folding and unfolding.

In testimony whereof I hereunto affix my signature in the presence of two witnesses.

JOHN T. FAIRHURST.

Witnesses:

LOUISE ENDERLE,
THOMAS A. HILL.
